UNITED STATES PATENT OFFICE.

AUSBERT H. WAGNER, OF CHICAGO, ILLINOIS, ASSIGNOR TO ANNA G. WAGNER, OF SAME PLACE.

BOILER.

SPECIFICATION forming part of Letters Patent No. 233,582, dated October 19, 1880.

Application filed September 8, 1880. (No model.)

To all whom it may concern:

Be it known that I, AUSBERT H. WAGNER, of Chicago, in the county of Cook and State of Illinois, have invented certain new and useful Improvements in Steam-Boilers, of which the following is a specification.

My invention mainly relates to improvements in upright tubular boilers or steam-generators, particularly that type of such class in which the generator is made in two parts, one section over the other.

My invention involves improvements in various parts of the mechanism, hereinafter first fully described preparatory to specific designation of the subject-matter claimed.

In the accompanying drawings my improvements are represented in connection with parts of an engine and a traction-wagon especially adapted to be operated thereby. Such parts constitute the subject-matter of another application, my present invention being confined to the boiler improvements.

Figure 1 is a plan or top view with a part of the top of the casing or hot-air jacket broken away. Fig. 2 is a view, partly in side elevation and partly in vertical longitudinal section on the line 2 2 of Fig. 1. Fig. 3 is a view, partly in rear elevation and partly in vertical transverse section on the lines 3 3 of Figs. 1 and 4. Fig. 4 is a transverse horizontal section on the line 4 4 of Fig. 3. Fig. 5 is a view in perspective, with some parts broken or in section, of the generator proper and its appurtenances or immediate connections. Fig. 6 is a front elevation of the engine proper—that is to say, the cylinder, crank-shaft, supporting-columns, &c.

A vertical sectional tubular generator or boiler, A A', is suitably supported and inclosed in a shell or casing, B, of a size sufficiently larger than the boiler to leave a space between the outside of the boiler and inside of the shell, constituting a hot-air space, B'. The flues b and b' of the lower or main section, A, and upper or top deck-section, A', of the boiler, respectively, are arranged in coinciding vertical planes—that is to say, each flue b' of the upper section, A', of the boiler is directly over or in line with its corresponding flue b of the main section A.

A space, B², separates the two sections and constitutes a flue-chamber, into which the smoke or products of combustion passing up the flues b from the furnace or fire-box C pass on the way to the hot-air space or jacket-chamber B'.

The upper section of the boiler is heated by radiation, by impingement of the flames; and by the waste products of combustion, as will readily be understood.

The fuel is supplied to the furnace by a central feeding cylinder or magazine, C'. Hard or soft coal or wood may be used as fuel.

The smoke-stack C² communicates with the hot-air space or jacket-chamber at its bottom only. (See Fig. 5.)

A vertical smoke-conducting chamber, D, is formed between two suitably secured vertical partitions, d d'. These division-plates d d' terminate a little above the bottom of the hot-air chamber or jacket-space B' and extend upward to the top of the boiler-section A'. The space B² is also closed between these plates in any simple way.

A single sheet of metal, bent at its edges to form the partitions d d', might be made to shut off communication between the chamber D and the flue-space B² in an obvious way.

The flanged base D' of the hot-air casing or jacket-shell B serves to secure it to a suitable foundation. Four screw-bolts, d², in this instance serve to removably attach the shell to the water-tank body D² of the traction-vehicle.

The upper and lower sections of the generator are connected in suitable way. One or more pipes leading from or near the top of the section A to or near the bottom of the boiler-section A' would answer, and steam passes to the steam-chest E by a pipe leading from the upper section, as will readily be understood without detailed description and illustration.

The boiler is, of course, to be supplied with water by a pump in proper way.

The fuel-magazine or fuel-cylinder is provided with a removable cover, e, at top, and terminates at its discharge end in a flaring serrated outlet a little below the level of the crown-sheet or lower flue-sheet of the boiler. This magazine extends through large central

openings or tubes in the two sections of the boiler.

The flues b' extend through the top section, A', of the boiler, and are adapted to be closed or opened at top by a perforated plate or register-disk, F, oscillating about the magazine-tube C'. The openings f in this register, when it is properly adjusted, coincide with the flues b' or openings through the top flue-sheet of the section A', as will readily be understood. A slot, f', and its pin serve to limit the movement of the perforated disk F, as usual in registers.

To facilitate the cleaning of the flues b and b' , and at the same time render unnecessary the exposure or opening at top of all the flues by the register F, a supplementary segmental cover or half-disk, E', is mounted to oscillate about the fuel-feeding cylinder on top of the register. When the register is adjusted to expose the flues it will be seen that the imperforate segmental plate resting on the register will cover some of the register-openings and consequently keep closed those of the flues which coincide with them while leaving open the remainder for cleaning by a suitable device inserted from above, and this without stopping the engine or materially interfering with the fire, draft, &c. The flues may thus be exposed successively in series—say half at a time—for cleaning. At other times all may be kept closed.

It will be seen that by the employment of the fuel-magazine the engine may be run for a long time at one firing up, and that by utilizing to the utmost the heat from the products of combustion, even while passing along the vertical chamber or smoke-conducting passage D to the outlet or smoke-stack, the fullest benefits from a given expenditure of fuel are attained.

In view of the prior state of the art, I do not broadly claim a boiler having a hot-air jacket, nor the division of the flues or arrangement of them in two sections, one above the other, so as to coincide; neither do I unqualifiedly claim the combination of such features, but concerning these and other parts confine my claims to subject-matter, essentially as below designated, distinguishing my improvements from prior inventions.

I claim as of my own invention—

1. The combination, substantially as here-

inbefore set forth, of the upright tubular sectional boiler, having the flue-chamber or horizontal space between the two sections, the shell or casing, with the hot-air space or jacket-chamber between it and the boiler, and the smoke-conducting chamber, by which the products of combustion pass from the bottom of said jacket-chamber to the outlet or smoke-stack.

2. The combination, substantially as hereinbefore set forth, of the upper and lower sections of the boiler, each provided with a series of flues, the upper series of flues coinciding with or arranged vertically over the flues of the lower series and separated therefrom by the flue chamber or space between the two sections of the boiler and the register-plate, by means of which the flues may be closed or exposed for cleaning throughout from above, as described.

3. The combination of the tubular upright boiler, the shell or casing, the register-plate, and the segmental plate, substantially as and for the purpose hereinbefore set forth.

4. The combination, substantially as hereinbefore set forth, of the shell or casing, the boiler composed of the upper and lower sections, having coinciding flues, and the horizontal space or flue-chamber between them, and the fuel-feeding cylinder passing centrally through said sections and flue-chamber.

5. The combination, in a steam-generator, of the hot-air jacket shell or casing, the upper and lower sections, A' A, having the coinciding flues and the space between them, the central fuel-feeding cylinder, the register-plate oscillating about said cylinder, and the segmental plate, also oscillating about the feeding cylinder, substantially as and for the purpose set forth.

6. The combination of the shell or casing B, the tubular boiler-sections A A', the flue-space B², the vertical partitions d d', between which the flue-space is closed, and the smoke-stack, substantially as and for the purpose hereinbefore set forth.

In testimony whereof I have hereunto subscribed my name.

AUSBERT H. WAGNER.
